By *Franklin & Mason,*

UNITED STATES PATENT OFFICE

ROBERT H. INGERSOLL, OF NEW YORK, N. Y., ASSIGNOR TO ROBT. H. INGERSOLL, INC.,
OF NEW YORK, N. Y., A CORPORATION OF NEW YORK

RAZOR STROPPER

Application filed July 26, 1927. Serial No. 208,484.

This invention relates to improvements in blade holders for employment during stropping.

One of the objects of this invention is to provide a structure of the class described which may be constructed of few and very simple parts, and is easily assembled by ordinary manufacturing operations. The several parts may be formed of sheet metal by an appropriate stamping and forming operation, and of bar material by appropriate automatic screw machine operations.

A further object is to provide a blade holder structure which may be easily brought into clamping relation with the blade and withdrawn therefrom for the purpose of securing and removing the blade.

Another object is to provide such a structure so that a strong support is formed for an open-end guard which protects the edge of the blade by rocking from side to side thereof during the stropping operation.

With these and other objects in view as will appear in the course of the following specification and claims, two examples of execution of the invention are set forth on the accompanying drawings.

Figure 1 is a plan view of a first modification of the device in stropping position.

Fig. 2 is a similar view, with the device in open position.

Fig. 3 is a section on line 3—3 of Fig. 1.

Fig. 4 is a plan view of a second form of execution in the stropping position.

Fig. 5 is a similar view in the open position.

Fig. 6 is a section on line 6—6 of Fig. 4.

In the modification of Figs. 1 to 3 inclusive, the device comprises an arched upper handle element 10 and an arched lower handle element 11, which are formed integrally with the respective upper blade holder 12 and lower blade holder 13, and are joined thereto by the bridge or arch portions 14. The blade holder 12 has a curled finger 15 at its free end which fits into an opening 16 in the free end of the holder, so that the two handles and holders may be swung with regard to each other from the position shown in Fig. 1 to that shown in Fig. 2.

The blade holders 12 and 13 are preferably

arched and of such dimension as to engage the double-edged razor blade B away from its center line to firmly support it during the stropping. The lower blade holder 13 has the studs 17 which are received in the usual apertures along the central line of the blade to hold the blade in its allotted position.

The handle element 13 is formed at its free end with a rivet 18 which passes through a slot 19 in a clip device 20 which is guided by the side walls 11^a of the handle element 11, and by the rivet 18. The clip device 20 also has a rivet 21 therein which engages in the stropping position in a notch 22 of the handle 10. As shown in Figs. 1 and 2, the sliding movement of this clip 20 and its rivet 21 is employed to lock and clamp the handles 10 and 11 together. The side flanges 10^a and 11^a of the handle are in abutting relation in the stropping position shown in Fig. 3, so that a firm and rigid structure is afforded when in clamping position.

A forked open-end guard is provided to protect the edge of the razor blade during stropping. This guard has the tines or guard rods 23 and the cross head 24 which connects these tines and joins them integrally with a stem or journal member 25 which has the cavities 26 along the axis of symmetry. A base plate 27 is secured to the handle 11 and has an upwardly and forwardly extending finger 28 which is received within one of the cavities 26. A second base plate 29 has an upwardly and rearwardly extending finger 30 which is received within the other cavity 26. The pivotal portion 25, 26 of the guard is located wholly within the handle and bridge; while the cross head 24 extends outwardly at either side through the notches 12^a, 13^a left at the sides of the bridges. The edges of the bridge members therefore define slots in the clamping position, the walls of which constitute stops to limit the guard in its rocking movement.

In the form of execution according to Figs. 4 to 6, the upper handle member 40 and the lower handle member 41 have the blade holder members 42 and 43 formed integrally therewith as before; and these members are in turn connected together by the curled finger 45 100

which engages in the eye 46. A tubular sleeve or clip 50 has a slot 49 therein to receive the rivet 48 which is connected in this instance to the upper handle member 40. The sleeve 50 slides back and forth in the handles 40, 41 as before, and carries an outer sleeve 51 which fits over the ends of the two handle members 40, 41 in the stropping position as shown in Fig. 6, and clamps these members together so that the holders 42, 43 are held upon the blade.

The lower holder 43 has the lugs 47 to support the blade as before. In this form it is preferred to form the handle members 40, 41 each as a half cylinder, so that a cylindrical sleeve is formed by the members when clamped together. On the half cylindrical handle 41 is supported a journal plate 47 which has the upstanding lugs 48 at each end and which are bent inwardly to form bearings to lie concentric with the axis of the assembled handles. A journal member 61 is closely received within these lugs 48 for rocking movement, and has at its ends the enlarged portions 62 which fit against the sides of the lugs 48 and thus assure the central portion 51 an invariable position for rocking. One of the enlarged portions 62 is formed with a transverse slot to receive the brace or cross-head 54 which supports the tines 53 of the guard. The brace 54 passes out through notches left at the bridge elements 44 which connect the handles 40, 41 together with the holders 42, 43, as in the first instance. These bridges also present their edges as before to form stops to limit the relative rocking movement of the guard and blade holder assembly.

The bearings for the journal member 25 or 40 61 are in each instance spaced apart in the line of the handle to maintain the parallelism of the guard rods with this line: and since the blade holder and handle are likewise in line, the guard rods are maintained in parallelism to the edge of the blade, regardless of their rocking from side to side.

The method of operating each of these devices is as follows: The device is held flat in the hand, and the clip member is pulled to the rear or to the right in the figures, until the upper handle member is free. This upper handle member and its associated holder 42 is then swung upwardly about the pivot 15, 16 so that the razor blade B is exposed, and may be withdrawn and replaced by another blade. The handle and holder 40, 42 is then swung back again and the clip 20 or 50 slid inward or toward the left until the handles and their holder elements are clamped firmly together. The handle is now taken in hand and the device is drawn back and forth across a strop, with a reversal at each end of each stroke about the guard associated with the edge being dressed. This is a natural movement, and after reversal the respective tines

23 or 53 must move from a position at one side of the edge to a position at the other side, and at all times protect the edge so that neither the strop nor the person of the operator is injured thereby.

The invention is not limited to the specific embodiments of the illustrations nor to use with double-edge blades, but its embodiments may be modified within the scope of the appended claims.

What I claim as new and desire to secure by Letters Patent is:

1. In a razor blade stropping device, a hollow handle having a blade holder connected therewith, said holder including elements to support the blade rigidly in line with the handle for stropping, the elements constituting said handle and blade holder having a slot therein intermediate the same, a rockable guard comprising a cross head and a guard rod fixed thereto, said guard rod being free at one end and spaced from the free end of the blade holder so that it is spaced from and parallel to the edge of the blade when in stropping position, said cross head extending through said slot, and pivot members fixed in said hollow handle to support said cross head, said pivot members being spaced apart in the direction of the line of the handle whereby to maintain said guard rod parallel to the edge of the blade.

2. In a razor blade stropping device, a handle, a blade holder connected therewith, said holder including elements to support the blade in line with the handle for stropping, and having a bridge connection rigid with said handle and holder to define guide slots, a rockable cross head passing through said slots and limited by the walls thereof in its rocking movement, guard rods each fixed at one end to said cross head to move therewith and being free at the other end, and means within said handle to support said cross head for rocking movement and being spaced apart in the line of said handle to maintain said guards parallel to the edge of the razor blade.

3. In a holder for razor blades for use during stropping, an integral member having a handle formed at one end thereon and a blade holder at the other end and with a notch intermediate said handle and blade holder, a second integral member likewise formed with a handle at one end and a blade holder at the other end, and with a notch intermediate its handle and blade holder, said members being formed with a pivot connection at the blade holder ends, said handle portion being arched to provide a hollow handle, journal bearing members secured to one of said integral members within the hollow of the handle, a rock shaft journaled in said bearing members and within said hollow handle, a cross head rigidly secured to said rock shaft and projecting through the said notches on said members to the exterior thereof, and a guard rigidly secured to the exterior of the handle, the guard being spaced from the edge of the blade when in stropping position, and being parallel to the edge of the blade.

idly carried by said cross head and maintained in parallelism with the edge of a razor blade by said bearing members.

4. In a holder for razor blades for use during stropping, two substantially straight integral members each formed with an annular arched handle portion at one end and having a blade holder at the other end, said members being pivoted together at the blade holder end, and being cut away intermediate the handle and blade holder portions to leave a slot therebetween when in the assembled position for stropping, means to secure said members together in the position for stropping to form a hollow handle, a rigid cross head extending through said slot from the exterior to a position between said members, a guard rigid with said cross head and carried thereby opposite the edge of a blade located in said blade-holder portions, a journal member fixed to said cross head and extending within said hollow handle, and a plurality of journal bearings fixed to one of said handle members and supporting said journal member, said bearings being spaced apart in the direction of the line of the handle so as to maintain said guards parallel to the edge of the razor blade and to permit said guards to rock from side to side of said edge, the walls of said slot forming stops in conjunction with said cross-head to limit such movement of said guard from side to side.

5. In a razor blade holder, a pair of members each constituting an integral handle and blade holder element, one of said members having blade receiving and retaining lugs secured thereto and directed toward the other member, said members being pivoted together to move toward and from one another for placing a razor blade on and removing the same from said lugs, said members when together constituting a blade holder device for securing the razor blade in position, means to clamp said members together in operative position, and a guard pivotally mounted on one of said members on the side thereof adjacent the other member so that the guard pivot mounting is located between the members when clamped together, said members being spaced apart so that said guard may project therethrough, the portions of said members so spaced apart constituting stops to limit the rocking movement of said guard.

In testimony whereof, I affix my signature.

ROBERT H. INGERSOLL.
